UNITED STATES PATENT OFFICE.

WALTER H. PIERCE, OF WATERTOWN, MASSACHUSETTS, ASSIGNOR TO CARR FASTENER COMPANY, OF CAMBRIDGE, MASSACHUSETTS, A CORPORATION OF MAINE.

FASTENER.

Application filed November 18, 1924. Serial No. 750,598.

This invention aims to provide an improved separable fastener.

In the drawings, which illustrate a preferred embodiment of my invention:—

5 Figure 1 is a plan view of one corner of a carpet showing an underlying fastener in dotted lines;

Fig. 2 is an enlarged section on the line 2—2 of Fig. 1;

10 Fig. 3 is a section of the parts as shown in Fig. 2, but showing the socket being engaged with the stud;

15 Figs. 4, 5 and 6 include a plan, a side and a bottom view respectively of the socket;

Figs. 7, 8 and 9 include a plan, a side and a bottom view, respectively, of the stud.

Referring to the embodiment of my invention, as illustrated in the drawings, I 20 have shown a simple, inexpensive pressed metal fastener herein described as a carpet fastener, but which may be used in many other instances where a simple snap fastener may be useful.

25 The stud, as illustrated, is pressed from a single piece of metal and has a flat base portion 1 presenting an inner wall 2 and an outer wall 3. These walls are formed so as to provide a rounded ring-like portion 4 connecting the upper ends thereof. The outer wall 3 is provided with an annular beaded portion or shoulder 5 providing a stud head and below the head a neck for engagement with a socket.

30 Both walls 2 and 3 are spaced apart for purposes more fully hereinafter disclosed. To permit contraction and expansion of the walls 2 and 3, I have divided them into a plurality of socket-engaging members by a 40 plurality of narrow slots 6. The slots cut through both walls and extend a slight distance into the base portion of the stud (Fig. 7), thereby permitting the socket-engaging members to bend mostly upon straight lines between the slots 6, in the material forming the base of the stud. If the slots stopped short of the base the socket-engaging members would bend on the curve of the wall 2 and would not be as resilient.

45 The stud may be secured to a flexible support or a rigid support as desired, but I have preferred to show it secured to a relatively thin floor 7 by means of a rivet 8.

50 This rivet, as illustrated, is pressed from the base 1 of the stud and extends through an

aperture in the floor so that a portion of it may be presented at the under side of the floor against which it is upset in the same manner as an eyelet.

55 The socket, which may be secured to a flexible support or to a rigid support, comprises a casing-like portion 9 pressed from a single piece of metal and presenting a stud-receiving aperture 10, surrounded by a continuous wall 11 preferably curved in 60 cross-section as shown in Figs. 2 and 3. This wall 11 is formed by bending or pressing a portion of the metal from the aperture 10 back upon the metal surrounding the aperture, and forms a smooth, guiding surface for cooperation with the stud during engagement and disengagement therewith. 65 Adjacent the periphery of the casing, I have provided a curved supporting portion 12, which rests against the floor and supports 70 the socket when engaged with the stud. At the outer periphery of the casing, I have provided a plurality of upwardly projecting attaching prongs 13, which pierce the 75 warp and weft threads of a carpet 14 and are bent outwardly and downwardly to hook over the web of the carpet as more fully shown and described in my co-pending application Serial No. 687,751, filed January 22, 1924.

80 During engagement of the socket with the stud, as illustrated in Fig. 3, the resilient portions of the wall 3 bend from the ring-like portion 4 and the wall 2 bends upon straight lines between the ends of the slots 85 6 as hereinbefore described, thereby contracting the shoulder portion 5 of the wall 3. The head of the stud may then pass through the aperture 10 in the socket and the socket-engaging portions then expand so that the 90 wall 3 engages the wall 11 surrounding the stud-receiving aperture 10. The head thereafter prevents separation of the stud and socket except when an upward pull is exerted upon the carpet 14. When the stud and socket are secured together, as shown in Fig. 2, the supporting portion 12 seats against the floor and supports the greater part of any weight applied directly over the fastener. 95 Thus, the fastener is protected from distortion when a person steps upon the carpet over the fastener or when some object is placed upon the carpet over the fastener.

100 While I have shown and described a preferred embodiment of my invention, it will 105

be understood that I have done so for purposes of clarification only, my invention being best defined in the appended claims.

I claim:

5. 1. A one-piece fastener stud comprising a base portion, an annular wall arising from said base portion, a second annular wall extending outwardly and downwardly from said first mentioned wall to provide a stud head and neck, and a plurality of slots extending through both walls to permit contraction and expansion thereof independently of each other.
10. 2. A one-piece fastener stud comprising a base portion, an annular wall arising from said base portion, a second annular wall extending outwardly and downwardly from said first mentioned wall to provide a stud head and neck, both of said walls slotted to provide resiliency and spaced apart so that they may expand and contract independently of each other during engagement and disengagement of a cooperating socket and an attaching rivet pressed from the center of
15. 20. 25. said base portion for securing the stud to a support.
3. A one-piece fastener stud comprising a

base portion, an annular wall arising from said base portion, a second annular wall extending outwardly and downwardly from 30 said first-mentioned wall to provide a stud head and neck, a plurality of slots extending through both walls to permit contraction and expansion thereof independently of each other, and means integral with said stud for 35 securing it to a stud support.

4. A fastener stud including a base portion presenting an upstanding peripheral wall, a second wall extending outwardly, downwardly and inwardly from said first mentioned wall to provide a shoulder adjacent the upper edge of said wall, said second wall terminating adjacent to the plane of the base portion, a plurality of slots terminating in said base and separating the 40 walls into resilient socket-engaging members adapted to flex upon straight lines passing through said base between the ends of 45 said slots, and a tubular rivet portion pressed from said base to secure the stud to a suitable support.

In testimony whereof, I have signed my name to this specification.

WALTER H. PIERCE.
